UNITED STATES PATENT OFFICE.

JOSEPH GANNON, OF WALTON, NEW YORK, ASSIGNOR TO STEINFELD BROS., OF NEW YORK, N. Y.

DESIGN FOR A TRAY.

61,225.

Specification for Design.

Patented July 18, 1922.

Application filed February 8, 1921. Serial No. 443,477. Term of patent 14 years.

To all whom it may concern:

Be it known that I, JOSEPH GANNON, a citizen of the United States of America, and resident of Walton, in the county of Delaware, State of New York, have invented a certain new, original, and ornamental Design for a Tray, of which the following is a specification, reference being had to the accompanying drawing, forming part thereof.

In the drawing, the figure is a perspective view of a tray embodying my design, and including as the distinctive feature of the design a base, a rail supported above the same, and ball-like elements on the rail.

I claim:

The ornamental design for a tray as shown and described.

JOSEPH GANNON.
